US00D581952S

(12) **United States Design Patent**
Hall et al.

(10) **Patent No.:** **US D581,952 S**
(45) **Date of Patent:** **** Dec. 2, 2008**

(54) **PICK**

(76) Inventors: **David R. Hall**, 2185 S. Larsen Pkwy., Provo, UT (US) 84606; **Ronald Crockett**, 2185 S. Larsen Pkwy., Provo, UT (US) 84606; **Scott Dahlgren**, 2185 S. Larsen Pkwy., Provo, UT (US) 84606; **Jeff Jepson**, 2185 S. Larsen Pkwy., Provo, UT (US) 84606

(**) Term: **14 Years**

(21) Appl. No.: **29/283,824**

(22) Filed: **Aug. 24, 2007**

Related U.S. Application Data

(63) Continuation-in-part of application No. 29/283,821, filed on Aug. 24, 2007, now Pat. No. Des. 566,137, which is a continuation-in-part of application No. 11/829,761, filed on Jul. 27, 2007, which is a continuation-in-part of application No. 11/773,271, filed on Jul. 3, 2007, which is a continuation-in-part of application No. 11/766,903, filed on Jun. 22, 2007, which is a continuation of application No. 11/766,865, filed on Jun. 22, 2007, which is a continuation-in-part of application No. 11/742,304, filed on Apr. 30, 2007, which is a continuation of application No. 11/742,261, filed on Apr. 30, 2007, which is a continuation-in-part of application No. 11/464,008, filed on Aug. 11, 2006, now Pat. No. 7,338,135, which is a continuation-in-part of application No. 11/463,998, filed on Aug. 11, 2006, now Pat. No. 7,384,105, which is a continuation-in-part of application No. 11/463,990, filed on Aug. 11, 2006, now Pat. No. 7,320,505, which is a continuation-in-part of application No. 11/463,975, filed on Aug. 11, 2006, which is a continuation-in-part of application No. 11/463,962, filed on Aug. 11, 2006, now Pat. No. 7,413,256, which is a continuation-in-part of application No. 11/463,953, filed on Aug. 11, 2006, which is a continuation-in-part of application No.

11/695,672, filed on Apr. 3, 2007, now Pat. No. 7,396,086, which is a continuation-in-part of application No. 11/686,831, filed on Mar. 15, 2007.

(57) **CLAIM**

The ornamental design for a pick, as shown and described.

DESCRIPTION

FIG. 1 is a side view of a pick showing our new design.

FIG. 2 is an opposing side view of the pick.

FIG. 3 is a top view of the pick.

FIG. 4 is a bottom view of the pick.

FIG. 5 is a bottom perspective view of the pick; and,

FIG. 6 is a top perspective view of the pick.

1 Claim, 2 Drawing Sheets
